EXCAVATING TOOTH

John F. Lindell, Newton, Iowa, assignor, by mesne assignments, to Koehring Company, Milwaukee, Wis., a corporation of Wisconsin

Application October 11, 1956, Serial No. 43,312

Term of patent 14 years

(Cl. D39—1)

Figure 1 is an end isometric view of an excavating tooth embodying my new design;

Figure 2 is a top perspective view of the tooth shown in Figure 1;

Figure 3 is a perspective view showing the bottom side of the tooth; and

Figure 4 is a side elevation thereof.

I claim:

The ornamental design for an excavating tooth, substantially as shown.
